UNITED STATES PATENT OFFICE.

HENRY DUKE WILLIAMS, OF NEW YORK, N. Y.

SAFETY LOCKING DEVICE FOR HATCH-DOORS.

1,204,221.

Specification of Letters Patent.

Patented Nov. 7, 1916.

Application filed May 23, 1916. Serial No. 99,462.

To all whom it may concern:

Be it known that I, HENRY D. WILLIAMS, a citizen of the United States, residing at New York, in the county of New York and State of New York, have invented certain new and useful Improvements in Safety Locking Devices for Hatch-Doors; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in safety devices for preventing accidents in hatches in connection with firerooms on torpedo boats.

In the fire rooms on torpedo boats, which are under forced air draft used for different purposes, in which the air is forced into the fire room by suitable blowers, the air going from fire rooms through air shutters into the fire box and up the stack, regulated according to the smoke, it is necessary, when the blowers are in operation, that, in the event of a person going through the bottom door, the upper hatch door be closed against being opened, otherwise serious injury might befall the person passing through the lower hatch door, which, in the event of both doors being opened at the same time, will cause the lower door to be blown closed with terrific force.

The present invention consists of an automatic means whereby, when the lower door is released, the upper door is held in a locked relation.

My invention consists of various details of construction, combinations and arrangements of parts which will be hereinafter fully described, shown in the accompanying drawings and then specifically defined in the appended claims.

I illustrate my invention in the accompanying drawings, in which:—

Figure 1 is a central vertical sectional view through the deck of a boat and a portion of the hatch, parts being in elevation, the door being shown as locked. Fig. 2 is a view in section through the deck showing

the latch released and the door opened. Fig. 3 is a sectional view on line 3—3 of Fig. 2.

Reference now being had to the details of the drawings by numeral 1 designates a hatch compartment with an opening 2 therein and in each compartment is positioned a ladder 2'.

3 designates a door, hinged at 6, to said opening and provided with a sight aperture 4. The outside of the door is provided with a handle 5 for convenience in opening and closing the same. Locking pawls 7 and 8 are mounted, the former upon a pivot 9 and the latter is pivotally mounted upon the pin 10, and 11 designates a bar to which the two locking pawls are pivoted, said bar being provided with a handle 12. The bar extends up through an aperture in the deck 18 and is pivotally connected at 14 with a link 15 which in turn is pivotally connected through the medium of a pin 16 with a movable pin locking member 17 which is L-shaped in section, as shown in Fig. 3 of the drawings. The portion of the hatch chamber which extends above the deck 18 has hinged thereto a top 19 with a beveled circumference 20 adapted to engage a similar beveled surface 21 upon the upper end 80 of the hatch compartment, as shown clearly in Fig. 1 of the drawings. Said cover is provided with a suitable sight opening 21' and has three locking bolts, designated respectively by numerals 22, 23 and 24, held 85 to the under surface of the cover by the straps 25. The two bolts 22 have pivotal connection through the medium of the pins 26 with corresponding ends of the angle levers 27 which are pivotally mounted upon 90 the pins 28 and the long arms of the angle levers 27 are pivotally connected through the medium of the pin 29 with the shank portion of the bolt 23 to which a handle 30 is connected by means of the links 31, shown 95 in Fig. 1 of the drawings. A coiled spring 32 is interposed between a strap 33 upon the under surface of the cover and a collar 34 and its purpose is to hold the various bolts normally in locked relation or in the 100 positions shown in Fig. 1 of the drawings.

It will be noted upon reference to Figs. 2 and 3 of the drawings that the inner surface of the upwardly projecting portion of

the hatch compartment has notches, designated by numerals 35, which are adapted to be engaged by bolts. A pin 37 is mounted in an aperture in the wall of the hatch 5 chamber and in alinement with the bolt 23 and serves as a means whereby, when pushed inward against the bolt 23, may cause the latter to disengage its notch in the wall of the hatch chamber and at the same time 10 cause the other bolts to be withdrawn, thus allowing the hatch door to swing open. When the member 17 is in the position shown in solid lines in Fig. 2, the L-shaped end of said member will be positioned over 15 the pin so that it will be impossible to release the bolts when the door is locked closed and which will be the position when the lower door 3 is opened.

From the foregoing, it will be noted that, 20 when the locking pawls 7 and 8 are in released positions, allowing the lower door to be opened, access may be had to the interior of the hatch chamber without any possibility of the top hatch door being opened 25 from the outside, thus avoiding any possibility of serious injury incident to both doors being opened at the same time.

What I claim to be new is:

1. A safety device for doors upon hatch 30 chambers upon torpedo boats, etc., comprising, in combination with a hatch chamber with a lower door and a door in the top thereof, movable locking pawls mounted upon the wall of the chamber and adapted 35 to lock said lower door closed, locking bolts upon the upper door, means for releasing said bolts, and mechanism actuated by said locking pawls for preventing the bolts from being released when the pawls are in un- 40 locked positions.

2. A safety device for doors upon hatch 45 chambers upon torpedo boats, etc., comprising, in combination with a hatch chamber with a lower door and a door in the top thereof, movable locking pawls mounted upon the wall of the chamber and adapted 50 to lock said lower door closed, locking bolts upon the upper door, means for releasing said bolts, a bar pivoted to the locking pawls, and means actuated thereby for preventing the bolt releasing mechanism from being operated when the pawls are in un- 55 locked positions.

3. A safety device for doors upon hatch 60 chambers upon torpedo boats, etc., comprising, in combination with a hatch chamber with a lower door and a door in the top thereof, movable locking pawls mounted upon the wall of the chamber and adapted 65 to lock said lower door closed, spring-pressed locking bolts upon the cover having pivotal connection with one another and adapted to engage notches in the wall of the hatch chamber, means upon the latter 70 for releasing the bolts, and means actuated

by the pawls for preventing said releasing mechanism being actuated when the pawls are in unlocked position.

4. A safety device for doors upon hatch 75 chambers upon torpedo boats, etc., comprising, in combination with a hatch chamber with a lower door and a door in the top thereof, movable locking pawls mounted upon the wall of the chamber and adapted to lock said lower door closed, spring-pressed locking bolts upon the cover having 80 pivotal connection with one another and adapted to engage notches in the wall of the hatch chamber, means upon the latter for releasing the bolts, a movable member 85 mounted upon the wall of the chamber and having pivotal connections with said locking pawls and designed, when the latter are in unlocked positions, to be positioned in the path of said releasing member to prevent the same being operated to release the 90 bolts.

5. A safety device for doors upon hatch 95 chambers upon torpedo boats, etc., comprising, in combination with a hatch chamber with a lower door and a door in the top thereof, movable locking pawls mounted upon the wall of the chamber and adapted to lock said lower door closed, spring-pressed locking bolts upon the cover having 100 pivotal connection with one another and adapted to engage notches in the wall of the hatch chamber, means upon the latter for releasing the bolts, a member having an L-shaped end which is slotted to receive 105 said member, and pivotal connections between said member and locking pawls.

6. A safety device for doors upon hatch 110 chambers upon torpedo boats, etc., comprising, in combination with a hatch chamber with a lower door and a door in the top thereof, movable locking pawls mounted upon the wall of the chamber and adapted to lock said lower door closed, spring-pressed locking bolts upon the cover having 115 pivotal connection with one another and adapted to engage notches in the wall of the hatch chamber, means upon the latter for releasing the bolts, a member having an L-shaped end which is slotted to receive 120 said releasing member, a bar pivotally connecting the locking pawls, and pivotal link connections between said bar and slotted member.

7. A safety device for doors upon hatch 125 chambers upon torpedo boats, etc., comprising, in combination with a hatch chamber with a lower door and a door in the top thereof, movable locking pawls mounted upon the wall of the chamber and adapted to lock said lower door closed, spring-pressed locking bolts upon the cover with pivotal angle lever connections, the wall of the chamber being notched for the reception of said bolts, a longitudinally movable 130

releasing pin mounted in an aperture in the wall of the chamber and in alinement with one of said bolts, a slotted L-shaped member through which said releasing pin passes, and connections between said slotted member and locking pawls.

In testimony whereof I hereunto affix my signature in presence of two witnesses.

HENRY DUKE WILLIAMS.
